ABSTRACT

A liquid-cooled housing for a rotary piston combustion engine consists of at least one annular shell and two parallel end pieces. The shell and end pieces contain chambers which are traversed by cooling liquid and are in communication with each other. Ports are sealed by gaskets at the juncture of the shell and end parts. These gaskets are recessed in encircling grooves close to the inner surface of the shell and are more or less parallel thereto near the outer periphery of the shell.

3 Claims, 3 Drawing Figures

LIQUID COOLED HOUSING FOR ROTARY PISTON COMBUSTION ENGINE

BACKGROUND OF THE INVENTION

Gaskets are ordinarily of elastic material, and are generally intended to supplement the seal due to metallic contact of the housing parts. The gaskets in the contemplated engines prevent passage of cooling liquid from the several ports along the meeting faces of the shell and end pieces, as well as to seal them against the working gases. The gaskets can perform their function only if they are correctly inserted in their accommodating grooves. When the housing is being assembled, loosely inserted gaskets may project from their grooves, or drop out partially or completely. This may have the unfortunate result that the gaskets are pinched and damaged, causing leaks between the shells and end pieces. Furthermore, the loose arrangement of the gaskets in their grooves causes difficulty in assembly because their correct location must be checked continually.

SUMMARY OF THE INVENTION

The object of the invention is to form the grooves receiving the gaskets in such a way that the gasket position in the groove cannot change.

This object is accomplished by providing at least one side wall of each groove with a plurality of projections to retain the gasket during assembly. Accordingly, each gasket may be secured in its groove when inserted with the aid of the projections, so that it cannot change position during assembly.

BRIEF DESCRIPTION OF THE DRAWINGS

An embodiment of the invention will be described in more detail with reference to the drawings in which:

FIG. 1 is a schematic end view in an axial direction of the shell of a rotary piston combustion engine of the trochoid type;

FIG. 2 is a fragmentary section through the shell and adjacent end piece taken along the line A—A of FIG. 1; and

FIG. 3 is an end view of a portion of a groove to a larger scale shown in the direction B in FIG. 2, and with the end piece omitted.

DETAILED DESCRIPTION

The illustrated liquid-cooled housing of a rotary piston combustion engine, consisting of a shell 1 and end pieces 2. The shell 1 and end pieces 2 contain cham-

bers 3 adapted to be traversed by cooling liquid. The chambers communicating with each other through ports 4 in the meeting faces or juncture of shell 1 and end pieces 2. This location is sealed by gaskets 5 and 6 recessed in encircling grooves 9 and 10 close to the inner surface 7 of the shell and more or less parallel thereto near the outer periphery 8 of the shell 1. The gasket cooperates in supplementing and reinforcing the seal due to metallic contact of the housing parts with each other.

5 10 15 20

As FIG. 3 shows, radial projections 11 are arranged in the side walls of grooves 9 and 10 in order to keep the inserted gaskets 5 and 6 therein and from being shifted or removed during assembly. The projections 11 may be arranged on either the inner or the outer side walls of grooves 9 and 10, or may be arranged in alternate fashion or both.

If the shell 1 is produced by die-casting, the grooves 9 and 10 together with the projections 11 may be advantageously cast, thus avoiding costly machining.

In an alternate embodiment grooves 9 and 10 may be alternatively arranged or staggered in the faces of the end pieces 2.

Thus the several aforesaid objects and advantages are most effectively attained. Although several somewhat preferred embodiments have been disclosed and described in detail herein, it should be understood that this invention is in no sense limited thereby and its scope is to be determined by that of the appended claims.

What is claimed is:

1. A liquid-cooled housing for a rotary piston combustion engine, comprised of at least one annular shell and two parallel end pieces, the shell and end pieces containing chambers traversed by cooling liquid and communicating with each other, ports in the meeting faces of the shell and end pieces communicating with the chambers, grooves encircling the ports close to the inner surface of the shell and essentially parallel thereto near the outer periphery of the shell, gaskets, the ports being sealed by the gaskets recessed in the encircling grooves, at least one side wall of each groove having a plurality of projections to retain the gasket during assembly.

2. The invention in accordance with claim 1, wherein both sides of said grooves have the projections.

3. The invention in accordance with claim 2, wherein the projections are in alternate staggered relationship.
